(57) **CLAIM**

The ornamental design for a vest as shown and described.

DESCRIPTION

FIG. 1 is a front view of the vest according to the present invention.

FIG. 2 is a rear view thereof.

FIG. 3 is a front perspective view thereof.

FIG. 4 is a rear perspective view thereof.

FIG. 5 is a right side view thereof with the right side strap shown unattached.

FIG. 6 is a left side view thereof.

FIG. 7 is a top view thereof; and,

FIG. 8 is a bottom view thereof.

The broken lines in the figures show portions of the vest which form no part of the claimed design.
